Attorney

UNITED STATES PATENT OFFICE

LLOYD F. BAILEY, OF LA PORTE CITY, IOWA

SMOKER'S APPLIANCE

Application filed March 19, 1931. Serial No. 523,867.

Heretofore, it has been the general practice to form the stem of a cigarette holder, or the stem of a pipe, of wood or other suitable composition providing a stem relatively hard and unyielding to the pressure of the teeth when the end of the stem is clamped between the teeth of the smoker.

One of the principal objections to such a stem, is that smokers having false teeth or dentures find that in using the cigarette holders or pipes provided with such a stem causes their plate to drop due to the pressure applied on the stem by the front or anterior teeth.

It is therefore the object of this invention to provide a stem for use either as a pipe stem or the stem of a cigarette holder which will have that end portion thereof usually clamped between the teeth of the smoker of a resilient nature yieldable to the pressure applied by the front or anterior teeth, thus overcoming the objections to the composition or wood stems now in use, and rendering the smoking of a pipe, or a cigarette from a holder enjoyable to those who, because of the objections above noted, the smoking of a pipe, or the smoking of a cigarette through a holder has been heretofore unpleasant.

A still further object of the invention is to provide a cigarette holder or pipe stem having a mouth piece of a substantially yieldable nature thus affording comfort to pipe or cigarette smokers.

Other objects and advantages of the invention will become apparent from a study of the following description, taken in connection with the accompanying drawings wherein:

Figure 1 is a perspective view of a cigarette holder embodying the features of the present invention.

Figure 2 is a perspective view of a pipe embodying the features of the present invention.

Figure 3 is a fragmentary longitudinal sectional view taken substantially on the line 3-3 of Figure 1.

Figure 4 is a transverse sectional view taken substantially on the line 4-4 of Figure 1.

Referring more in detail to the drawings, and especially to Figure 1, it will be seen that I have shown a cigarette holder the same

including the cigarette accommodating socket 5 and the stem portion 6. According to the present invention, I employ a tube 7 of metal or other suitable material extending longitudinally through the bore of the stem 6 and at one end projecting beyond the stem 6 at that end of the stem remote from the socket 5. On the outer free end of the tube 7 there is provided a sleeve 8 formed of rubber or other suitable yieldable material, and anchored to the tube 7 against longitudinal or rotative movement relative to the tube through the medium of prongs 9 radiating from the tube and embedded within the material of the sleeve 8. At the outermost end of the sleeve 8 there is provided a cap 10 that is suitably secured to the tube 7, and is provided with a counter bore for receiving a reduced end of the sleeve 8 as at 11. The stem 6 is also provided with a counter-bore for receiving the reduced end of the sleeve 8 as at 12. Thus the sleeve 8 is securely positioned on the tube at the end of the stem 6 thus providing a yieldable mouth piece for the stem which will yield to the pressure exerted thereon by the teeth when the holder is held between the teeth of the smoker.

As suggested in Figure 1, the sleeve 8 at that end thereof adjacent the cap 10 may be flattened at the top and bottom to accommodate the lips of the smoker.

In Figure 2 I have shown the invention as applied to the pipe and from a study of the figure, it will be seen that the tube 7a is disposed in the bore of the pipe stem 13 and the sleeve 8a on the outer end of the tube being positioned at the end of the stem 13 thus providing a yieldable mouth piece for the stem of the pipe. The sleeve 8a is disposed between the free end of the pipe stem 13 and a suitable cap or head 10a disposed at the outermost end of the tube 7a.

From the foregoing then it will be seen that I have provided a yieldable mouth piece for the stem either of a cigarette holder, or a pipe, and the same will provide a cushion for the teeth between which the stem is clamped, and the yieldability of the mouth piece or sleeve will in no wise cause smok-

ers having dentures or false teeth such inconveniences to which they are subjected when using a pipe, or cigarette holder the stem of which is relatively hard and has no yielding properties. Further, it will be apparent that the invention may be readily applied to the stem of a cigarette holder, or pipe by merely increasing the diameter of the bore of the stem. Such a mouthpiece, then, as contemplated by the present invention may be used as a part of the stem of a cigarette holder or pipe, or may be provided as an article of manufacture separate and independent of the stem and readily applied to the stem of a conventional cigarette holder or pipe.

Even though I have herein shown and described the preferred embodiments of the invention, it is to be understood that the same is susceptible of changes, modifications and improvements coming within the scope of the appended claim.

Having thus described my invention, what I claim as new is:

A mouthpiece for the stem of a cigarette holder, pipe or the like comprising a tubular core and a sleeve formed of a yieldable material on one end of said core, and penetrating prongs radiating from said core and embedded in said sleeve for securing the latter against movement relative to the core.

In testimony whereof I affix my signature.

LLOYD F. BAILEY.
